FREDERICK SCHERR, JR., AND BYRON P. LUCE, OF FAJARDO, PORTO RICO.

GROOVE-CLEANER FOR ROLLING-MILLS.

1,212,116.

Specification of Letters Patent.

Patented Jan. 9, 1917.

Application filed November 9, 1915. Serial No. 60,535.

To all whom it may concern:

Be it known that we, FREDERICK SCHERR, Jr., and BYRON P. LUCE, citizens of the United States, and residents of Fajardo, 5 Porto Rico, have invented a new and Improved Groove-Cleaner for Rolling-Mills, of which the following is a full, clear, and exact description.

Our invention relates to groove cleaners 10 for the grooved rolls of a rolling mill, and is primarily intended as a cleaner for the grooves of the rolls of a sugar-cane mill. Sugar-cane mill rolls having deep circular 15 grooves have to be cleaned continually, otherwise the grooves will very quickly fill up with bagasse and become useless. Heretofore said grooved rolls were cleaned by a series of steel teeth or scrapers entering the 20 grooves, the cleaning edge of said scrapers forming an angle of about 90° with the tangent to the roll, said scrapers being rigidly mounted on a crossbar extending parallel to the roll. The result was that the 25 bagasse would accumulate at the ends of the scrapers and jam itself into the clearance between the scraper and the sides of the grooves, gradually producing such strains as to break the scrapers or bend and even break the crossbar. This not only 30 causes considerable expense and loss of time, but the whole contrivance acted as a powerful brake on the circumference of the rolls, absorbing considerable power, which was an absolute loss.

To obviate the above defects we have 35 designed a cleaner which is simple, easily installed, interchangeable and easily and quickly adjusted for any slight variation that may occur in the distance between the 40 grooves of the various rolls.

With the above objects in view, the nature of which will more fully appear as the description proceeds, the invention consists in the novel construction, combination and 45 arrangement of parts as herein fully described, illustrated and claimed.

In the accompanying drawings, forming 50 part of the application, similar characters of reference indicate corresponding parts in all the views.

Figure 1 is a fragmentary cross section through the roll of a mill provided with our cleaner; Fig. 2 is a fragmentary side elevation of the rolling-mill frame, showing 55 a grooved roll with the cleaners there-

for; and Fig. 3 is a cross section of the blade of the cleaner on line 3—3, Fig. 1.

Referring to the drawings, 3 represents a grooved roll of a sugar-cane mill, the spaced grooves 4 of which receive a blade 5 the 60 stem 6 of which engages the socket of a bracket 7. The blade is clamped in place on the socket by a set screw 8. The bracket is in turn clamped on a tubular shaft or crossbar 9 extending parallel to the grooved 65 roll 3. A clamp 10, forming part of the bracket, grips the shaft 9 and permits the rotation of the bracket on the shaft and also the longitudinal displacement thereof upon said shaft. The shaft 9 is prevented 70 from turning by bearings 11 which clamp the shaft to the frame of the mill.

The blade is preferably triangular in contour and it is so designed as to present two edges thereof tangent to the bottom of the groove at two different points of the circumference. The edge 13 is the cleaning edge and is maintained substantially tangent to the bottom of the groove at a point ahead of the edge 15, which is the contacting or supporting edge of the blade. The 75 contacting edge 15 facilitates the setting of the blade relative to the groove of the roll which forms a support for the blade at the working end thereof by the engagement 80 of the edge 15 with the bottom of the groove, thereby eliminating any strain tending to bend or break the blade or the means securing it. Due to the design of the blade, 85 so that the two edges thereof, 13 and 15, are substantially tangent to the bottom of the groove at different points, the end 12, formed by the intersection of the said edges, is ahead of the point of contact of the edge 15 with the bottom of the groove, 90 thus eliminating all possibility of the blade digging into the roll, for the bagasse never reaches the bottom of the groove in one revolution of the roll.

The adjustability of the brackets 7 on the shaft 9 allows the necessary compensation for the variation in distance between the grooves or different rolls. The wear of the blade is taken up by the adjustment of the 100 blade within the bracket.

We claim:

1. The combination with the grooved roll of a mill of cleaning means for the grooves, comprising a triangular-shaped blade for each groove and means for presenting two 110

edges of the blade tangentially to the bottom of the groove at different points.

2. The combination with the grooved roll of a mill of cleaning means for the grooves, comprising a triangular-shaped blade for each groove, said blade having a cleaning edge and a contacting edge, means for maintaining the contacting edge in engagement with the bottom of the groove, said cleaning edge being so related to the contacting edge that the same is in a substantially tangential direction with the bottom of the groove.

3. The combination with the grooved roll of a mill of cleaning means for the grooves, comprising a blade for each groove, said blade having a contacting edge and a cleaning edge, and means for maintaining the contacting edge against the bottom of a groove, the apex formed by the cleaning and contacting edges of the blade adapted to be disposed ahead of the radius joining the center of the roll and the point of contact.

4. The combination with the grooved roll of a mill of cleaning means for the grooves, comprising a triangular-shaped blade for each groove, each of the blades having a stem extending from one of the apexes of the blade, a bracket for each stem in which the stem is free to turn and slide, means for securing the stem to the bracket, and a cross bar adapted to extend parallelly to the roll for supporting said brackets, each of said brackets having clamping means for adjustably securing said brackets on to the bar, each bracket being adapted to maintain one edge of the blade in contact with the bottom of the groove, another edge of the blade being tangential to the bottom of the groove.

40 5. The combination with the grooved roll of a mill of cleaning means for the grooves, comprising a triangular-shaped blade for each groove, each of said blades having a stem extending from one of the apexes, each 45 of the blades having a contacting and a

cleaning edge, the apex formed by said edges being the attacking end of the blade, a bracket for each blade having a socket in which the stem is adapted to slide and turn, means for securing the stem to the socket, and a tubular bar adapted to extend parallelly to the roll for supporting the brackets, each of the brackets having clamping means for securing the bracket to the bar and whereby the socket of the bracket can be adjusted laterally and transversely of the bar, each bracket being adapted to maintain the contacting edge of the blade against the bottom of the groove, the cleaning edge of the blade being so related to the contacting edge that the same is substantially tangential to the bottom of the groove when the contacting edge of the blade is in engagement with the bottom of the groove.

6. As an article of manufacture, a triangular-shaped blade for cleaning circular grooves, said blade having an edge for engaging the bottom of a groove and an edge to be disposed tangentially to the bottom of the groove when the first-mentioned edge is in contact with the bottom of the groove, the cross section of the blade increasing from the first-mentioned edge toward the second, said blade having a stem for securing the blade.

7. As an article of manufacture, a cleaning blade for grooved rolls adapted to present two edges substantially tangential to the bottom of a groove at different points thereof, one of said edges being adapted to engage the bottom of the groove when pressure is applied to the other of said edges.

In testimony whereof we have signed our names to this specification in the presence of two subscribing witnesses.

FREDERICK SCHERR, Jr.
BYRON P. LUCE.
